UNITED STATES PATENT OFFICE.

AUGUST GIESE, OF NEW YORK, N. Y.

DESIGN FOR A FAUCET-BODY.

SPECIFICATION forming part of Design No. 29,025, dated July 12, 1898.

Application filed June 15, 1898. Serial No. 683,523. Term of patent 14 years.

To all whom it may concern:

Be it known that I, AUGUST GIESE, a citizen of the United States, residing in the city of New York, borough of Brooklyn, county of 5 Kings, and State of New York, have invented and produced a new and original Design for Faucets, of which the following is a full, clear, and exact description.

The leading feature of my design is a faucet-body of essentially the configuration represented in the accompanying drawings, 10 wherein—

Figure 1 shows a side view, and Fig. 2 a central longitudinal section, of the faucet embodying my design.

In the drawings, *a* is a tubular faucet-casing surmounted by a tubular column *b*. From one side of the faucet-casing a curved tubular delivery member *c* projects in one direction, and from the other side of the faucet-casing a 20 curved tubular delivery member *d* extends in an opposite direction and terminates in a spirally-ribbed portion *e*.

What I claim is—

The design for a faucet-body, substantially 25 as shown and described.

AUGUST GIESE.
